(57) **CLAIM**

The ornamental design for a clamp light, as shown and described.

DESCRIPTION

FIG. 1 is an isometric view of a clamp light.

FIG. 2 is another isometric view of the clamp light of FIG. 1.

FIG. 3 is a front view of the clamp light of FIG. 1.

FIG. 4 is a right side view of the clamp light of FIG. 1.

FIG. 5 is a rear view of the clamp light of FIG. 1.

FIG. 6 is a left side view of the clamp light of FIG. 1.

FIG. 7 is a top view of the clamp light of FIG. 1; and,

FIG. 8 is a bottom view of the clamp light of FIG. 1.

The broken lines form no part of the claimed design.
